PLATE OR SIMILAR ARTICLE

Fridolin Blumer, Cold Spring, N.Y., assignor to Oneida
Ltd., Oneida, N.Y., a corporation of New York

Filed Dec. 11, 1959, Ser. No. 58,637

Term of patent 14 years

(Cl. D44—15)

The figure is a plan view of a plate of conventional configuration showing my new design, conventional color shading being employed on the leaf elements.

The essential feature of my design resides in the ornamentation applied to the plate.

I claim:

The ornamental design for a plate or similar article, substantially as shown and described.
